(57) **CLAIM**

The ornamental design for footwear, as shown and described.

DESCRIPTION

FIG. 1 is a perspective view illustrating the design of an embodiment of a left foot footwear according to the present invention.

FIG. 2 is a right-side view of a left or right foot embodiment of footwear of the present invention.

FIG. 3 is a left-side view of a left or right foot embodiment of footwear according to the present invention.

FIG. 4 is a rear view of a right foot embodiment of footwear according to the present invention.

FIG. 5 is a front view of a right foot embodiment of footwear according to the present invention.

FIG. 6 is a top view of a left foot embodiment of footwear according to the present invention, illustrating the left foot of a user in dashed line; and,

FIG. 7 is a bottom view of a left foot embodiment of footwear according to the present application.

A right foot embodiment of footwear is a mirror image of a left foot embodiment of footwear.

The dashed lines in FIG. 6 are used to illustrate a foot environment and form no part of the claimed design.

1 Claim, 3 Drawing Sheets
